UNITED STATES PATENT OFFICE.

RALPH ABRAHAM SCHOENBERG, (NOW BY JUDICIAL CHANGE OF NAME RALPH A. BELMONT,) OF NEW YORK, N. Y., ASSIGNOR TO THE CONNECTICUT ELECTRIC MFG. CO., OF BRIDGEPORT, CONNECTICUT, A CORPORATION OF CONNECTICUT.

FUSE-PLUG.

1,277,647.

Specification of Letters Patent.

Patented Sept. 3, 1918.

Application filed November 3, 1914. Serial No. 870,049.

To all whom it may concern:

Be it known that I, RALPH A. SCHOENBERG, of New York, in the county and State of New York, have invented a new and useful

5 Fuse-Plug, of which the following is a specification.

Heretofore the lining of fuse plugs has been brittle being made usually of porcelain or other vitreous material which is likely to 10 be broken or fractured by a blow or fall and particularly in shipping with the result that pieces have blown out and have caused much damage and have also increased fire hazard. Moreover such breaking or fracture often 15 causes a failure to make contact owing to mechanical disarrangement of the parts of the fuse and the fuse wire itself is sometimes actually broken or disarranged when the plug is screwed in position.

20 A feature of my invention which overcomes these defects is the use of an insulating material which is non-brittle and not easily breakable such, for example, as fiber, which is non-combustible but at the same 25 time lacks the brittleness of such materials as glass or porcelain.

Another feature of my invention is the lightness of the fuse plug which is particularly important in shipping and is due to the 30 large air chamber in the fuse plug.

Another feature of my invention is its cheapness and uniformity of construction as all the parts can be made by tools while heretofore shrinkage and the fitting of the 35 parts together have caused much difficulty.

Another feature of my invention is that the current can not jump as has been the case heretofore on account of the breaking or chipping of the brittle and readily breakable 40 material such as porcelain.

Another feature of my invention consists in providing an outlet for the gases at the base of the plug so that the danger of fire will be eliminated.

45 Another feature is the large space provided for the gases when fusion takes place which reduces immensely the chances of fire and makes my plug much safer than those heretofore known.

50 Another feature is the use of a washer or washers to hold the center contact in place.

In the drawings:

Figure 1 is a top plan;

Fig. 2 is a section on line 2—2 of Fig. 1;

55

Fig. 3 is an inverted plan;

Fig. 4 is a detail of the center contact

plug;

Fig. 5 is a perspective view of the lining;

60

Figs. 6 and 7 are plans respectively of the

inner and outer washers;

65

Fig. 8 is an end view of the screw shell;

and

Fig. 9 is a modification.

Referring to Figs. 1 to 8 of the drawings, 70

1 represents the shell body of my improved fuse plug, said shell being formed with exterior screw threads so that the plug can be

screwed into a socket in the usual fashion.

The inner end of shell 1 is made with an 75

inturned flange 2 that is formed with four crimps 3 which provide as many elevated

seats upon the inner side of said flange and four radial channels or grooves upon the 80

outer side of said flange. The four seats provided by the crimps 3 support a washer 4

of non-brittle insulating material, preferably compressed fiber, provided with a central aperture 5, and four peripheral notches 6.

The central aperture accommodates the 85

center contact 7 of the plug which, at its outer end has mounted upon it a washer 8

of non-brittle insulating material, preferably compressed fiber, that is held in position 90

against the outer side of flange 2 by the head 9 of contact 7. The shank of contact 7

85 consists of two prongs 10 which are bent or upset so as to clamp washers 4 and 8 firmly to flange 2. Within the shell 1 is arranged

a lining 11, Fig. 5, of non-brittle sheet material, preferably compressed fiber, that snugly

fits the interior of shell 1 and within which the washer 4 fits snugly. This lining 11 is

made from a strip of sheet material of the character specified, formed at one corner with a notch 12 and rolled into cylindrical 95

form.

It will be clear that with a given size of

plug I provide a very large chamber for the

gases so that danger of explosion is reduced

to the minimum, it being borne in mind that

heretofore the interior of the shell has been

very largely occupied.

100 Within the crotch of contact 7 is soldered

one end of the fuse 13 whose opposite end

extends through notch 12 and is soldered to

105 the inner side of shell 1. When this fuse

13 burns out the gases are free to pass out of shell 1 through the notches 6, the space 14 between washer 4 and flange 2, the aperture 15 surrounded by flange 2 and the channels 5 provided upon the exterior of the latter by crimps 3. Thus it will be seen that the gases are discharged from the inner end of the plug and into the socket within which the plug is mounted, thus greatly reducing 10 the fire risk.

Near its outer end the shell 1 is made with an annular crimp which provides a shoulder against which a ring 17 is clamped by an out-turned flange 18 at the outer end of shell 15. This ring 17 is of non-brittle insulating material, preferably compressed fiber. A disk 21 of mica or other suitable transparent insulating material is placed against flange 18 and held in place by a metal ring 19 surrounding said disk and ring 17, said metal ring having at its outer end an inwardly extending flange 20 bearing against the outer side of disk 21 and being turned or crimped inwardly against ring 17 as at 22 so that the 20 disk 21, flange 18, ring 17 and ring 19 are clamped securely together and cannot be 25 rotatively displaced relatively when ring 19 is grasped and rotated to insert the plug 19 in its socket or remove it therefrom.

30 In Fig. 9 I have shown another form of shell 1 having a sinuously crimped flange 23 at its upper end on which the washers 4 and 8 are seated, the undulations providing radial gas channels between the flange and 35 washers upon both sides of said flange.

What I claim is:

1. A fuse plug comprising an exterior screw threaded metal shell; a center contact secured to and supported by one end of said 40 shell; a plurality of insulating members between said shell and said center contact and spaced apart to provide a gas outlet; a fuse within said shell connecting the latter with said contact; a closure for the opposite end 45 of said shell; and a metallic cap clamping said closure to an insulating flange at said opposite end of said shell.

2. A fuse plug comprising a side contact; a fuse chamber; a center contact at the bottom of said chamber and an outlet for gases at that end of the plug at which the center contact is located, said outlet being indirect from said chamber to the atmosphere.

3. A fuse plug comprising a shell with 55 an inturned flange having radial grooves; a washer inside of said flange; a washer outside of said flange; and a center contact held by said washers, said flange holding said washers in spaced relation to form an outlet for gases.

4. A fuse plug comprising a shell with an inturned flange; a washer engaging the inside of said flange but having a portion spaced from said flange to provide a gas 65 outlet; a second washer engaging the out-

side of said flange but having a portion spaced from said flange to provide a gas outlet; and a center contact held in place by said washers.

5. A fuse plug comprising a shell body 70 member; an outwardly extending flange of insulating material fastened to said shell; a lining for said shell; spaced washers at one end of said shell; a center contact secured to and supported by said members; a 75 fuse within said shell connecting the latter with said contact; a closure of insulating material for opposite end of shell, said closure being clamped to the outwardly extending flange.

6. A fuse plug comprising a metal shell having an inwardly extending flange at one end; an outwardly extending insulating flange fastened to the other end of said shell; a center contact supported by said inwardly 85 extending flange; spaced insulating material between said shell and said center contact; a fuse within said shell connecting the latter with the center contact; a closure for the end of said shell opposite said center contact; 90 and a metallic cap clamping said closure to said outwardly extending flange.

7. A fuse plug comprising a screw threaded metal shell made at one end with an in-turned flange; a closure for the opposite 95 end of said shell; a non-brittle insulating lining for said shell; a washer of non-brittle insulating material secured to said flange; a center contact carried by said washer and a fuse connecting said center contact and 100 shell; said flange being formed with outlet passages for the gases.

8. In a fuse plug the combination of a shell having a flange at each end; an insulating ring engaging one of said flanges; an 105 insulating cover at one end of said shell; a ring engaging said cover and insulating ring to clamp them to said one flange; a contact at the other end of said shell; and insulation for said contact attached to the other 110 of said flanges.

9. In a fuse plug a shell with an inturned flange having a plurality of portions struck up at one surface and grooved on the other; a washer seated on said struck up portions; another washer partially closing said 115 grooves; and a center contact held in place by said washers.

10. In a fuse plug the combination of a screw shell having a shoulder and an outwardly-extending flange near one end; an insulating ring clamped between said shoulder and flange; a closure for said end of the shell; and a metal ring formed with a flange and surrounding said insulating ring and 125 said closure and clamping them together and to the flange on the screw shell.

11. A fuse plug comprising a screw shell body member; a center contact; a plurality of insulating members to insulate said con- 130

tact from and attach it to said body member and holding said contact in position, said members being spaced to provide an outlet for gases.

5 12. A fuse plug comprising a shell with a flange; a center contact; a plurality of insulating members held in spaced relation by said flange and held together by said contact, said insulating members keeping the 10 shell and center contact in insulated relation, but permitting the escape of gases between said insulating members.

15 13. A fuse plug comprising a screw shell body member; a chamber; a fuse in said chamber; a center contact connected to said fuse; insulating members supporting said center contact and insulating it from said body member and located at the bottom of said chamber and perforated to receive said 20 center contact; an outlet for gases between said insulating members and independent of said perforations.

25 14. A fuse plug comprising a chamber; a fuse in said chamber; a center contact connected to said fuse at the inside of the device; a support for said contact located at the bottom of said chamber; and an outlet for gases at that end of the plug at which the center contact is located.

30 15. A fuse plug comprising a shell body member with an inturned flange having raised and grooved portions; a washer inside of said flange; a washer outside of said flange; a center contact holding said washers in spaced relation with said flange; and a fuse connecting said center contact and shell body member.

16. A fuse plug comprising a shell with an inturned flange; a center contact; insulating means connecting the center contact 40 with said flange; and a gas outlet between said means and said flange.

17. A fuse plug comprising a screw shell body member; a hollow vented chamber within said member; a center contact; a 45 vented insulating support for the center contact connected to said member; and a fuse connecting said contact and body member together.

18. In combination a fuse plug comprising a screw shell contact member; flanges on opposite ends of said member, the flange on one end holding an insulating ring; a cover over said one end and on said ring and clamped to said ring, the flange on the 55 other end having raised and grooved portions; spaced washers on opposite sides of the last-mentioned flange; an insulated vented chamber; a center contact; and a fuse connecting the shell contact and said center 60 contact.

19. A fuse plug comprising a side contact; a fuse chamber; a center contact at the bottom of said chamber; a fuse connecting said contacts; insulating material supporting said center contact; an insulating tube forming the inner wall of said chamber; and an outlet for gas between said insulating material.
